YARN CLAMP

Charles F. Brown, Pawtucket, R. I., assignor to
 Hemphill Company, Pawtucket, R. I., a corpora-
 tion of Massachusetts

Application October 11, 1951, Serial No. 250,879

4 Claims. (Cl. 66—145)

1

This invention relates to an improvement in yarn clamps for a circular, independent needle, knitting machine. Its object is to effectively prevent the overfeeding of yarn when a yarn lever is moved out of action and until it goes into action again.

When a yarn lever of a circular, independent needle knitting machine is moved from an active to an inactive position, the yarn is guided by the needles and by the yarn lever into a binder and cutter. To insure this, the yarn should remain under tension. If there is slack in the yarn adjacent the needles at this time, the probability is that it will not be properly bound and cut. Such slack may occur as the result of the abruptness of the movement of the yarn lever, vibration, or other causes. Devices to overcome this difficulty have taken the form of clamps of various types positioned as near to the needle circle as is conveniently practicable. Usually, such clamps are operated by the mechanism which operates the yarn levers. However, as a rule, they are inefficient because they do not become effective until the yarn lever approaches its inactive position, whereas they should operate as soon as possible after the yarn lever has left its feeding position and, in reverse, release the yarn too soon as the yarn lever returns to its feeding position. Furthermore, too much operating energy is required. This strains the yarn lever operating mechanism and, not infrequently, damages it.

The purpose of this invention is to provide a yarn clamp which is extremely simple and inexpensive and which is effective to clamp the yarn almost immediately when the yarn lever starts to rise or otherwise move out of its feeding position.

One type of clamp of this invention, applied to a circular, independent needle knitting machine of the "Banner" type, is shown in the drawing, of which:

Figure 1 is a side elevation;
 Figure 2 is an end elevation;
 Figure 3 is a detailed view corresponding to a part of Figure 1; and

Figure 4 is a view similar to Figure 3, showing a structural modification.

As shown in Figure 1, the machine is provided with yarn levers such as 1, pivotally mounted in the usual way on an extension 2 of the carrier ring 3. Yarn lever 1 may be moved from its yarn feeding position to its inactive position (shown in dotted and dash line in Figure 1) by usual means (not shown). When such means operates to so move the yarn lever, lever

2

4 will be swung towards the vertical by projection 5 of the yarn lever. Since lever 4 is held in contact with projection 5 of the yarn lever 1 by spring 6, it may be used effectively to operate the yarn clamp of the type with which this invention is concerned.

This clamp consists of a suitable plate 7 so mounted upon the machine as to overlie the upper end of lever 4. The underside of plate 7 adjacent the end which projects towards the cylinder of the machine is provided with a transverse notch 8, the front edge of which consists of a substantially vertical wall 9 and the rear edge of which is bevelled as shown at 10 in Figures 1, 3 and 4. Penetrating plate 7 and communicating with the bottom of notch 8 is a hole 11 through which the yarn 12 is threaded. Consequently, yarn 12 passes through notch 8 on its way to the yarn lever.

20 Affixed by one end to the underside of plate 7, as at 13, is a light, concavo-convex leaf spring 14. This spring is in alignment with lever 4 and, also, is so positioned that, when yarn lever 1 is in yarn feeding position and lever 4 is consequently in its forward position, as shown in Figure 1, the upper end of lever 4 will closely underlie spring 14 at a point in front of the bottom of the downward curve of the spring. As soon as yarn lever 1 is caused to leave its yarn feeding position, lever 4 will be swung towards the vertical with the result that its tip 15 will immediately engage spring 14 and force it upwardly so that the free end 16 of spring 14 will engage bevel 10 of notch 8 and will then move upwardly and forwardly along this bevel as the result of consequent reduction in the curvature of the spring until it strikes the lower corner of wall 9. Since yarn 12 passes between the end 16 of spring 14 and wall 9, it will be clamped securely very shortly after the movement of the yarn lever begins and any further motion of the yarn lever and, consequently, of lever 4, will tend to elongate spring 14 and thus add additional clamping force to the spring. See Figure 3.

40 When the yarn lever action is reversed and yarn lever 1 moves from its inactive to its yarn feeding position, the release of the yarn from the yarn clamp is delayed until the motion of the yarn lever is substantially completed. Thus, the yarn 12 remains taut and proper feeding to the needles is assured.

50 The forward end of spring 14 is preferably bent into a cylinder as shown but, of course, this shape may be altered to any other desired one

which can cooperate effectively with notch 8 to clamp the yarn as already described.

Plate 7 may be made of any desired material but it is well known that some materials are so soft that the forward wall 9 of notch 8 might become grooved by the fast running yarn so that the clamp would become ineffective. In fact, any material will become so grooved in time so that it is desirable to make the forward wall 9 of notch 8 of a resistant material and replaceable.

Such a modification is shown in Figure 4 where forward wall 9 is shown as the rear edge 18, of a separate piece 17 attached to plate 1 which has been made correspondingly thinner as at 19, to accommodate piece 17. This piece may be made of porcelain, for example, which is the usual material for yarn guides and it may be replaceably affixed to plate 7.

Another advantage of considerable importance gained by the use of this invention is that very little energy is required to cause lever 4 to operate spring 14. Present day yarn clamps, designed for equivalent usage, require the application of very considerable energy derived from the mechanism which operates the yarn levers. This has resulted too frequently in the bending of parts of this mechanism.

I claim:

1. In a circular, independent needle, knitting machine, a yarn clamping mechanism comprising a clamping plate, a recess in said plate through which yarn may pass, a curved leaf spring attached to said plate in such a manner that when said spring is at rest it is spaced from the surface of said recess but is engageable therewith and thereafter, by a reduction in its curvature, it is adapted to clamp said yarn between said spring and a wall of said recess and means for forcing said spring into engagement with said recess and for elongating said spring by reducing its curvature.

2. A yarn clamping mechanism for a circular, independent needle, knitting machine having a yarn lever comprising a lever associated with said yarn lever, and a clamping plate having a recess in its surface, an aperture in said plate for admitting yarn to said recess, a curved leaf spring attached to said plate and adapted to enter said recess and clamp said yarn when the curvature of said spring is reduced, said plate being so positioned that said lever reduces the curvature of said spring when the yarn lever is removed from its yarn feeding position.

3. A yarn clamping device comprising a clamping plate having a recess in one surface thereof, an aperture in said plate for admitting yarn to said recess, and a curved leaf spring adapted to enter said recess and clamp said yarn when the curvature of said spring is reduced.

4. A yarn clamping device having a clamping plate with a recess in one surface thereof through which yarn may pass, one side of said recess being substantially perpendicular to said surface, the opposite side of said recess sloping from said surface toward said perpendicular side, and a resilient yarn clamping member normally spaced from said sides of said recess and adapted to be moved into contact with said sloping side and said perpendicular side.
